UNITED STATES PATENT OFFICE.

HARRY R. PENNINGTON, OF CHICAGO, ILLINOIS, ASSIGNOR TO JOHN A. AMOS, OF ST. LOUIS, MISSOURI.

ELECTRICAL ATTACHMENT PLUG.

Application filed April 25, 1923. Serial No. 634,425.

To all whom it may concern:

Be it known that I, HARRY R. PENNINGTON, a citizen of the United States of America, residing at the city of Chicago, 55 State of Illinois, United States of America, have invented a certain new and useful Electrical Attachment Plug, of which the following is such a full, clear, and exact description as will enable anyone skilled in the art 60 to which it appertains to make and use the same, reference being had to the accompanying drawings, forming part of this specification.

A variety of electrical devices, such as 65 portable lights, heating units and devices operated by small motors, are commonly attached to electrical circuits by means of attachment plugs and receptacles, and in order that a defect in one of these devices which 70 would result in the "blowing" of the line fuse, may not interrupt the service of other electrical devices attached to the same circuit, it has been proposed to embody protective fuses in attachment plugs.

75 My invention relates to plugs of this type and its object is to simplify the construction, and to provide means whereby renewable fuse strips may be employed, and readily inserted and removed, thus producing a 80 smaller and less expensive plug than would be necessary if cartridge fuses were employed. In my improved plug the fuse chambers are formed by recesses in the insulating material of the plug.

85 In the accompanying drawings Figure 1 is a cross-sectional view, along the line 1-1' of Figure 2, of an attachment plug embodying my invention and shown installed in a protective metal casing which may or may not 90 be employed; Figure 2 is a rear end view of the device shown in Figure 1; Figure 3 is a top plan view of the lower part of the plug; Figure 4 is a plan view showing the under-surface of the upper part of the plug.

95 The plug casing is of insulating material and is divided longitudinally into two parts, 1 and 2. Part 1 is provided with longitudinal recesses 3 and 4 separated by the barrier 5, and in these recesses are secured fuse terminals 6 and 6'. Contact members 7 and 8 are also secured to the part 1, and in the form illustrated in the drawings these contact members are provided with extensions 9 forming fuse terminals. Separation of

the two parts of the plug gives access to the 55 fuse chambers and permits the insertion or withdrawal of the fuse strips 10.

The other part 2 of the plug casing is provided with longitudinal recesses 3' and 4' conforming with the recesses in part 1, these 60 recesses being separated by the barrier 5', which together with barrier 5 completely separates the fuse chambers when the parts are in assembled relation.

The part 2 of the casing carries resilient 65 contact members 11, so proportioned and positioned that when the parts of the casing are brought together they press the ends of the fuses into good electrical contact with the fuse terminals 6 and 6', and the extensions 70 9 of the contact members 7 and 8, which in the particular construction shown form the cooperating fuse terminals.

The parts of the plug are held together by the screw 12, and if desired the plug may 75 be inserted in a protective metal casing 13 and held in position therein by the screw 14 passing through the plug as shown. The line wires are attached to the plug by means 80 of the clamping screws 15.

It will be noted that my improved plug as described, comprises a structure in which blown fuses can be easily and cheaply renewed and one in which necessary size is not substantially increased by the incorporation 85 of fuses.

Having fully described my invention what I claim as new and desire to secure by Letters Patent of the United States is:

90 1. An electrical attachment plug comprising a two part casing, one of which is provided with fuse terminals, a fuse, and resilient clamping means carried by the other part of the plug to hold the fuse in engagement with the terminals when the plug parts 95 are in assembled relation.

100 2. An electrical attachment plug comprising a casing divided longitudinally into two parts, one of said parts being provided with a longitudinal recess on its inner face forming a fuse chamber, a renewable fuse strip and terminals therefor in said chamber, and a pair of resilient members carried by the other part of the casing 105 and positioned to extend into the fuse chamber and press the fuse strip into conductive engagement with the terminals when the casing parts are in assembled relation.

3. An electrical attachment plug comprising a casing of insulating material divided longitudinally into two parts, one of said parts being provided with longitudinal recesses on its inner face forming fuse chambers and provided with fuse terminals and contact members, renewable fuse elements in said chambers, and resilient elements on the

other part of the casing adapted to press the fuses into contact with the terminals and 10 contacting members when the casing parts are in assembled relation.

In testimony whereof, I have hereunto set my hand and affixed my seal.

HARRY R. PENNINGTON. [L.S.]
